Clemir J. Ney, of Lowell, Mass.

Assignor to.

The Lowell Manufacturing Company.

Letters Patent No. 1730, dated Mar. 3. 1863.

The schedule referred to in these Letters Patent and making part of the same.

To all whom it may concern:

Be it known that I, Clemir J. Ney, of Lowell, in the County of Middlesex, and State of Massachusetts, now temporarily residing in New York, have originated and designed a new Pattern for Carpets or other fabrics, of which the following is a full, clear and exact description, reference being had to the accompanying drawings making part of this specification.

Fig. A, is one half of a large group, consisting of four large flowers arranged about four smaller ones; groups of leaves extend from between the large flowers, and the whole group is interspersed with small balls. B, is one half of a set group of leaves and flowers resting on a ground which is enclosed by a triple octagonal frame. 1, and 2, at the sides, when matched form a set group of leaves resting on a ground which is surrounded by bands of lace work. Fig. 3, is a small group of leaves and flowers, from which radiate branches of sprigs. In the four corners are sections of figures similar to 3. The colors employed for the different portions of the design may be varied to suit the taste and wish of the manufacturer.

~ claim. ~

What I claim as my invention and desire to secure by letter patent, is the design or pattern for carpets or other fabrics herein set forth.
